[57] CLAIM

The ornamental design for a facsimile device, as shown and described.

DESCRIPTION

FIG. 1 is a front elevational view of a facsimile device showing our new design;

FIG. 2 is a top plan view thereof;

FIG. 3 is a left side elevational view thereof;

FIG. 4 is a right side elevational view thereof;

FIG. 5 is a rear elevational view thereof;

FIG. 6 is a bottom plan view thereof; and

FIG. 7 is a top plan view showing the state of use in which the facsimile device is combined with an acoustic coupler.

The broken line showing of the acoustic coupler in FIG. 7 is for illustrative purposes only and forms no part of the claimed design.

FIG. 1

FIG. 2

FIG. 3

FIG. 4

FIG. 5

FIG. 6

FIG. 7
